AEROPLANE MOUNTING

Eldon L. Dale, Long Beach, Calif., assignor, by direct and mesne assignments, to Dale Radio-
plane Co., a corporation of California

Application May 10, 1937, Serial No. 141,664

3 Claims. (Cl. 272—31)

This invention relates to an aeroplane mounting, particularly for toy aeroplanes and the prime object of my invention is to provide a mounting for an aeroplane which is revolvable about a central tower and which permits the plane to loop while revolving about the central pivot, the looping of the plane being accomplished by the pull of the propeller and the lift of the wings and without other controls or power applied to the mounting arm.

Still another object is to provide an aeroplane mounting of the character stated, which is simple in construction, is effective and realistic in use and further, which is relatively inexpensive to manufacture.

Other objects, advantages and features of invention may appear from the accompanying drawing, the subjoined detailed description and the appended claims.

20 In the drawing:

Figure 1 is a side elevation of the aeroplane mounting with parts broken away to show interior construction.

Figure 2 is a top plan view of the same.

25 Figure 3 is a side elevation of the aeroplane mounting showing the driving motor and mounting arm also in side elevation.

Figure 4 is a fragmentary plan view of the pivotal mounting for the arm.

30 Figure 5 is a fragmentary plan view of the inner end of the mounting arm.

Referring more particularly to the drawing, the numeral 1 indicates the central tower about which the toy aeroplane 2 revolves. The toy aeroplane includes the usual wings 3, and a driving propeller 4. The method of driving said propeller will be further described. A trunnion 5 is journaled in the top of the tower 1 and a ring 6 is integrally formed with the trunnion 5 and 35 is positioned on the top thereof. A ball 7 is pivotally mounted in the ring 6 on the pintles 8—8. The ball 7 is thus permitted to pivot in a vertical plane. An electric motor 9 is attached to one side of the ball 7 by suitable means usual 40 and well known in the art. A sleeve 10 is attached to the ball 7 and projects substantially horizontally therefrom on the side opposite to which the motor 9 is attached. The motor 9 receives its power through wires 11 shown di- 45 grammatically in Figure 1. Sliding contacts 12 on the trunnion 5 convey the current to the motor 9 and also permit horizontal and vertical movement of the parts as will be further described. The speed of the motor is controlled 50 from the rheostat 13, the rheostat being placed

at a distance from the tower 1. An arm 14 is journaled in the sleeve 10 at its inner end and the outer end of the same is curved in a horizontal plane as shown at 15, so as to enter the fuselage of the plane 2 as shown in Figure 2. The outer end of the arm is also bent downwardly in a vertical plane as shown at 16. The curves 15—16 permit the plane to loop as it revolves about the trunnion 5 as will be evident from analyzing the forces exerted by the propeller 4 and the lift 5 of the wings 3. It is noted that there is a lever arm extending from the center line of the arm 14 indicated at C in Figure 1 and extending to the line A B in Figure 1. The propeller 4 exerts a force in the line A B and the lift of the wings 3 15 exerts a force at right angles to this line A B. This last named force extends upwardly. The component of these two forces then, is a line extending upwardly at an angle to the line A B and consequently the plane will revolve around the point C, when the speed of the propeller 4, i. e. the forward speed of the plane is sufficiently high. The lifting force of the wings and the forward force of the propeller 4 are all exerted in a plane displaced horizontally from the point 20 C. This is evident from viewing Figure 2. The curve 15 accomplishes this purpose and again there is a lever arm, the length of which is from the center line of the arm 14 to the plane of lift of the wings 3. This will also tend to cause 25 the plane to loop or revolve around the center line of the arm 14. The propeller 4 is driven from the motor 9 by a flexible wire 17 which extends through the arm 14 and is attached to the armature of the motor. When the propeller 30 4 is not revolving, the aeroplane would tend to hang close to the floor, with the propeller 4 pointing downwardly. To prevent this, I provide a stop for the arm 14, so that when idle the aeroplane will assume an inclined position substantially as shown in Figure 1. This stop consists of a finger 18, which is attached to the ring 6. A notch 19 is provided in the side of the arm 14, which notch is engaged by the finger 18 when the aeroplane is not in flight. As soon as the propeller 4 is driven, the aeroplane will lift the arm 14 35 upwardly, thus disengaging the finger 18 and permitting the arm 14 to revolve when the aeroplane is looping. It will be evident from the foregoing description, that the electric motor 9 counter- 40 balances the aeroplane 2 and further, that the center of the motor is directly in line with the arm 14, thus permitting the driving cable or wire 17 to pass directly from the armature of the motor into the arm 14 and thence to the propeller 45 50 55

4. By regulating the speed of the motor from the rheostat 13, the speed of the propeller will be varied and the aeroplane will rise and fall as it revolves about the tower 1, and at high speeds of the propeller, the aeroplane will loop around the arm 14.

Having described my invention, I claim:

1. An aeroplane mounting comprising a central tower, a trunnion pivotally mounted in the tower, an arm journaled on the trunnion, said arm being mounted for vertical movement, a driving motor on one side of the trunnion, an aeroplane mounted on the outer end of the arm, a propeller on the aeroplane and a flexible cable extending from the motor through the arm and thence to the propeller, whereby the propeller is driven by the motor and a remote rheostat controlling the speed of said motor, said arm being curved in a horizontal plane as it enters the aeroplane and said arm being curved downwardly and in a vertical plane at the outer end thereof.
2. An aeroplane mounting comprising a central tower, a trunnion pivotally mounted in the tower, an arm journaled on the trunnion, said arm being mounted for vertical movement, a driving motor on one side of the trunnion, an aeroplane mounted on the outer end of the arm, a propeller on the aeroplane and a flexible cable extending from the motor through the arm and thence to

the propeller, whereby the propeller is driven by the motor and a remote rheostat controlling the speed of said motor, said arm being curved in a horizontal plane as it enters the aeroplane and said arm being curved downwardly and in a vertical plane at the outer end thereof, and disengagable means engaging the arm when the aeroplane is at rest, whereby said arm is prevented from rotating.

3. An aeroplane mounting comprising a central tower, a trunnion pivotally mounted in the tower, an arm journaled on the trunnion, said arm being mounted for vertical movement, a driving motor on one side of the trunnion, an aeroplane mounted on the outer end of the arm, a propeller on the aeroplane and a flexible cable extending from the motor through the arm and thence to the propeller, whereby the propeller is driven by the motor and a remote rheostat controlling the speed of said motor, said arm being curved in a horizontal plane as it enters the aeroplane and said arm being curved downwardly and in a vertical plane at the outer end thereof, a fixed finger adjacent the arm and means on the arm engageable by the finger when the aeroplane is at rest, whereby said arm is prevented from rotating.
